[57] CLAIM

The ornamental design for a steam head for a bath or shower enclosure, as shown.

DESCRIPTION

FIG. 1 is a perspective view of a steam head for a bath or shower enclosure showing my new design;

FIG. 2 is an elevational view of one side thereof;

FIG. 3 is a front elevational view thereof;

FIG. 4 is a elevational view of the side thereof opposite that shown in FIG. 2;

FIG. 5 is an elevational view of one end thereof;

FIG. 6 is an elevational of the end thereof opposite that shown in FIG. 5; and,

FIG. 7 is a rear view thereof.

FIG. 1**FIG. 2****FIG. 3****FIG. 4****FIG. 5****FIG. 6****FIG. 7**
